UNITED STATES PATENT OFFICE.

JOHN WALDHEIM, OF ELIZABETH, NEW JERSEY, ASSIGNOR TO UNDERWOOD TYPE-WRITER COMPANY, OF NEW YORK, N. Y., A CORPORATION OF DELAWARE.

TYPEWRITING MACHINE.

Application filed August 20, 1921. Serial No. 493,786.

To all whom it may concern:

Be it known that I, JOHN WALDHEIM, a citizen of the United States, residing in Elizabeth, in the county of Union and State of New Jersey, have invented certain new and useful Improvements in Typewriting Machines, of which the following is a specification.

This invention relates to sound-deadening cases or hoods for typewriting machines of the continuous billing variety, one form of which machine is shown in the patent to Wernery & Smith, No. 1,132,055, granted March 16, 1915. The sound-deadening casing or hood is of the general type disclosed in my prior application, Serial No. 466,820, filed May 4, 1921 (now Patent No. 1,519,645, dated December 16, 1924).

In the Underwood continuous billing or fan-fold machine, the usual letter-feeding carriage has a rearward extension, upon which a carbon-sheet carriage may move forwardly and rearwardly. Plies of work-webs, fed in from the rear of the machine, are interleaved with the carbon-sheets attached to said carbon-carriage, and the webs and carbon-sheets are drawn forwardly around the platen to the printing point. The webs usually comprise a succession of similar printed forms, and, when a form has been typed, the platen is swung upwardly and forwardly in a swing-frame mounted on the carriage, to permit the sheets to be straightened out so that the carbon-sheets may be more easily retracted to co-operate with a fresh portion of the work-webs. The typed forms are then gaged against a gage carried by the platen-swing-frame and severed by a knife carried by said frame adjacent the platen.

The present invention provides a hood or casing which deadens the noises arising in the typing operation, while permitting easy access to and operation of the machine. For this purpose, the casing comprises a body-part and a cover-part or cover hinged at the rear to said body-part, said body-part being provided with a large front opening to permit passage of the machine therein, and being sufficiently large to receive the entire machine with the exception of the banks of keys which project forwardly from the body-part. A cover-plate is mounted at the front of the body-part to close the front opening

therein. The cover-part encloses the machine at the top and terminates at the front 55 a short distance above the cover-plate, to form a slot through which various operating handles on the carriage may pass to project outside of the casing; sound-deadening means being provided to close the slot. To 60 permit easy access to the typewriter-carriage and to the carriage-extension, upon which is mounted the carbon-carriage and over which pass the work-webs, and to enable the platen-swing-frame to be swung upwardly and forwardly, the cover-part is hinged near the extreme rear of the body-part, so that, when said cover-part is raised, the entire carriage and carriage-extension will be exposed. With the cover-part in raised position, the 70 platen-frame may be swung upwardly and forwardly to permit the work-webs to be straightened under the platen in the usual manner and for the usual purpose. At certain times it is desired merely to have access 75 to the platen and its associated mechanism, as for the purpose of making erasures, or for adjusting the work-webs around the platen. It is therefore a feature of this invention to provide the cover-part with an auxiliary 80 front door or cover which may be raised or lowered independently of the main cover-part to permit access to the mechanism at the front of the machine. Said front cover is preferably provided with a window to permit the machine in the interior of the casing 85 to be viewed.

Another feature of this invention is the provision of means whereby work-webs may be fed continuously through said casing 90 to the machine, without removing any part of the casing or forming an outlet for sounds.

Still another feature of the invention relates to means for releasing and lifting the cover by a single finger-piece. 95

Other features and advantages will hereinafter appear.

In the accompanying drawings,

Figure 1 is a side view, vertically sectioned, of the sound-deadening casing or hood applied to an Underwood continuous billing or fan-fold machine. 100

Figure 2 is a detail of a latch for holding the cover-part in position and means for simultaneously releasing the latch and raising the cover-part. 105

Figure 3 is a plan view, partly sectioned, of the device shown in Figure 1.

Figure 4 is a front view, partly sectioned, of the device shown in Figure 1.

5 Figure 5 is a view similar to Figure 1, but with parts broken away, and showing the cover-part in raised position, and the swinging platen-frame in its upward and forward position.

10 The Underwood continuous billing machine comprises a main frame 10 supported by feet 11 upon a base, said main frame having a forward extension 12 in which are positioned banks of keys 13, operating

15 type-bars 14 to cause types 15 carried by said type-bars to print against a platen 16 mounted in a platen-frame 17. Said platen-frame forms part of a carriage 20 mounted for letter-feeding movement upon a front

20 rail 21 and a rear rail 22 on the main frame 10. Said carriage is provided with a rearward extension 25 supported at its rear upon a rail 26 on a rearward extension 27 of the main frame 10, said carriage-exten-

25 sion 25 having side rails 28 upon which is mounted for forward and rearward movement an auxiliary carbon-carriage 29, having stepped side pieces 30 upon which are positioned clip-bars 31 for fastening car-

30 bon-sheets 32 to said carbon-carriage.

Plies of work-webs 35 are led over a guide-bar 36 on the rear of the extension 25 between side gages 37 and interleaved with the carbon-sheets 32. The work-webs 35 and carbon-sheets are then led forwardly beneath the platen to the printing point. The work-webs 35 usually have printed thereon a series of similar successive forms, each of which is typed and torn off before

40 the next form is in position to be typed. When a form has been fully typed, the platen 16 is swung upwardly and forwardly by means of a swinging frame 39 in which said platen is journaled, said swinging

45 frame being pivotally mounted in the end walls of the platen-frame 17. The platen being thus swung upwardly and forwardly enables the work-webs and carbon-sheets to be straightened out, so that little resistance

50 is offered when the carbon-sheets are retracted to cooperate with a fresh portion of the webs by pushing rearwardly a handle 40 fixed to the carbon-carriage 29, the rearward movement of said carbon-carriage 55 being limited by a stop 41. The typed work-webs are then gaged against a gage 42 carried by the swinging frame 39, and are severed by a front knife 43 carried by said frame.

To effect rotation of the platen, 60 the end of the platen-shaft 45, by which said platen is journaled in said swinging frame, is provided with a gear-wheel 46 in mesh with a gear-wheel 47, the axis of said gear-wheel 47 being the axis about which 65 the platen-frame is rotated, so that said

gear-wheel 46 will be in mesh with said gear-wheel 47 at all times. To rotate said gear-wheel 47, there is provided a gear-wheel 48 fixed to a shaft 49, journaled in the end walls of the platen-frame 17 and 70 operated by a knob or finger-wheel 50, or by suitable line-spacing mechanism, not shown.

To deaden the sounds arising in the typ- 75 ing operation, there is provided a sound- deadening casing or hood having a body- part indicated generally at 60, and a cover- part indicated generally at 61 and hinged to said body-part on the rear thereof at 62, said body-part comprising a rear wall 64, 80 side walls 65 and a front wall in the form of two end portions 67, said end portions being spaced apart to permit the insertion of the machine into the casing. The body- part is provided with lateral extensions 66 85 over which the typewriter-carriage and its extension operate to the right and left, and with a rearward overhanging extension 69, in which the rear of the carriage-extension 90 25 operates. When the machine is positioned within the casing, the forward ex- tension or keyboard extension 12 extends forwardly from the casing to expose the banks of keys 13. To close all of the front 95 opening not occupied by said forward ex- tension 12, there is provided a front cover- plate 70, mounted upon said end portions 67 by means of turn-buttons 71, having latches 72 fixed thereto, said latches passing 100 through openings in said end portions and catching behind said end portions to fix the cover-plate in position. The body-part thus completely encloses the entire machine, with the exception of the forward extension 12, 105 at the rear, sides, and front, said extension 25 of the carriage operating to the right and left over the lateral extensions 66 and in said rearward extension 69.

To enclose the machine at the top, there is provided the cover-part 61, comprising a for- 110 wardly-extending top wall or ceiling 75, and a forwardly and downwardly extending front wall 76, in which is positioned a transparent plate 77 to permit the machine in the in- 115 terior of the casing to be viewed. The front wall 76 of the cover-part terminates above the upper edge of cover-plate 70 to form a space at the front through which various carriage-operating levers, such as the line- 120 space handle 78, may extend. All of said slot not actually occupied by the carriage- operating levers is closed by a strip or cushion 79 of sound-deadening material, the two-ply edges of which are fixed upon the upper edge of the cover-plate. The cover- 125 part may be normally pressed toward open position by means of a spring 82 fixed at its forward end at 83 to the body-part, and at its rearward end at 84 to an arm 85 fixed to the cover-part, so that said spring tends 130

to draw said arm forwardly, and hence rotate said cover-part upwardly about hinge 62.

To maintain the cover-part in closed position, there is provided a latch 86 fixed at one end of a short shaft 92 rotatably mounted in a side wall of the cover-part, said latch being operable by a handle 87 fixed to the other end of shaft 92 on the 10 outside of said cover-part. The latch engages a pin 88 on the body-part and is normally pressed into engagement with said pin by a spring 89. By properly rotating handle 87 against the action of spring 89, 15 the latch 86 may be released, the handle 87 serving as a means to assist in raising the cover-part.

In a continuous billing or fan-fold typewriting machine, continuous webs 35 are fed to the machine, and this invention provides means whereby said webs may be fed to said machine from outside said casing without necessitating removal of any part of the casing, and without providing an outlet 20 through which sounds may pass. Said means comprises a slot 90 in the body-part, directly to the rear and beneath the guide-bar 36, through which the work-webs 35 may pass, the slot being closed by felt strips 91 25 fixed one to each side of the slot, so that the surfaces are in engagement with the surfaces of the work-webs, said strips thus closing all of the slot not occupied by said webs. The slot 90 extends completely across 30 the casing, and, when the carriage and its extension move laterally from right to left, the work-webs will be carried between gages 37 to the right and left, sliding in said slot 35 between said felt strips 91.

It will be apparent that the cover-part hinged at the rear at 62 to said body-part will, when opened, expose substantially the entire carriage and carriage-extension. Thus, in the position shown in Figure 5, the 40 cover is raised to such a height as to permit the swinging frame 39 and the attached gage 42 to swing freely to its forward and upward position. The upward movement of the cover-part 61 may be limited by pin 101 on the body-part which engages the arm 85 fixed to said cover-part. However, where it is not desired to have access to the carriage-extension, or where the swinging frame 39 is not to be operated forwardly, 45 it is inconvenient to raise the entire cover-part. Thus, if erasures are to be made on the work-webs at the front of the platen, or where the webs are to be adjusted in position around the platen, it is sufficient to provide access merely to the front of the machine. For this purpose, the front wall 50 of the cover-part 61 is constructed in the form of an auxiliary door or cover hinged at its upper end at 105 to the main cover-part, and swingable upwardly to expose the

front of the machine. The cover 76 is provided with a finger-piece 106 whereby said cover may be operated independently of the cover-part, the latter being opened by operation of the handle 87.

Variations may be resorted to within the scope of the invention, and portions of the improvements may be used without others.

Having thus described my invention, I claim:

1. A sound-deadening casing to enclose a machine of the class described and permit operation thereof from the outside, comprising a body-portion to receive the machine and having a rear overhang and lateral overhangs to accommodate the machine, and a hinged cover to be swung upwardly and rearwardly to permit upward and forward swinging of the platen-displacing frame of the machine and to give access to the carbon-carrier thereof.

2. A sound-deadening casing to enclose a machine of the class described and permit operation thereof from the outside, comprising a body-portion to receive the machine and having lateral overhangs to accommodate the travel of the carriage and the carbon-carrier track, and a cover hinged at its rear to said body-portion to be swung upwardly to permit upward-and-forward swinging of the platen-displacing frame, and to give access to the carbon-carrier, said body-portion having, adjacent the rear end of the carbon-carrier-track, a slot to provide for the passage of continuous webs into the casing adjacent the rear end of said track, and for transverse movement of the webs with the carriage, and means to seal said slot around said webs.

3. A sound-deadening casing to enclose a machine having a platen, a traveling carriage therefor, a rearward extension thereof to travel therewith, a carbon-retracting device on said extension, and a platen-displacing frame on said carriage, comprising a body-portion to receive the machine and having lateral overhangs to accommodate the travel of said carriage and its extension, and a cover hinged at the rear of said body-portion to be swung upwardly to permit upward-and-forward swinging of the platen-displacing frame, and to give access to the carbon-carrier, said cover having hingedly connected at its front end a door openable to give access to the upper front part of the machine without lifting the cover.

4. A casing for deadening the sound of operation of a continuous billing typewriting machine comprising a carriage, a rearward extension thereof, and a carbon-retracting device on said extension, said casing comprising a body-part having lateral overhangs to accommodate the travel of said carriage and its extension, and a cover-part hinged at the rear to said body-part so that

- raising of the cover-part exposes said carriage and extension, said cover-part having hingedly fixed thereto an auxiliary cover operable independently of the rest of the 5 cover-part for permitting access to the front of the machine without raising the cover-part, a handle for raising said front cover independently of the cover-part, and a handle for raising said cover-part as a unit.
- 10 5. A sound-deadening casing to enclose a machine having a platen, a carriage therefor, a platen-displacing frame on said carriage, a rearward extension of said carriage, a carbon-retracting device on said extension, and a web-guide on the rear end of 15 said extension to guide webs to the carbon-retracting device, said casing comprising a body-portion to receive the machine and having lateral carriage-accommodating overhangs, a rearward overhang with a slot, through which the webs pass to said guide, and a roof over the rear end of said extension and over the rearward overhang, and a cover hinged at the forward edge of said 20 roof to be swung upwardly to permit upward-and-forward swinging of the platen-displacing frame, and to give access to the carbon-carrier, said cover having at its front a forwardly and downwardly inclined door 25 hinged at its upper edge to give access to the upper front part of the machine without lifting the cover, and a finger-piece at the lower edge of said door to lift the same independently of the cover.
- 30 6. A casing for deadening the sound of operation of a typewriting machine, comprising a body-part and a cover-part hinged to said body-part, spring means normally tending to raise said cover-part, a latch normally urged to effective position for holding said cover-part in lowered position against the action of said spring means, a handle mounted on said cover-part to lift the cover-part and having a limited movement before 35 lifting the cover-part, and means actuatable by said handle, in such limited movement, to release said latch.
7. A sound-deadening casing to enclose a machine of the class described and permit 40 operation thereof from the outside, comprising a body-portion to receive the machine, an upwardly-urged cover hinged at the rear of said body-portion to be swung upwardly to permit upward-and-forward swinging 45 of the platen-displacing frame, and to give access to the carbon-carrier, and cover-latching means including a hook on the inner side of and pivoted to a side wall of said cover, and a pin on said body-portion to be engaged 50 by said hook, a stop-pin on said side wall to limit the releasing movement of the hook, and a finger-piece on the outer side of said side wall, to swing said hook against said stop-pin to release the cover, and then to 55 urge the cover upwardly.
8. A sound-deadening casing for a machine of the class described, having at its front an opening through which the keyboard projects and a slot through which controlling handles project from the carriage, and comprising a body-portion with side walls comparatively low at the front to expose the ends of the carriage and comparatively high along the carbon-carrier-extension, and a cover hinged at its top and 70 rear to said body-portion and having side walls to fit the side walls of the body-portion, a ceiling at a sufficient elevation to accommodate the gage bar on the platen-displacing frame and the carbon-carrier handle, and a transparent wall at the front to permit work 75 on the platen to be viewed.
9. A sound-deadening casing for a machine of the class described, having at its front an opening through which the keyboard projects and a slot through which controlling handles project from the carriage, and comprising a body-portion and a cover hinged at its top and rear to said body-portion and having a ceiling at a sufficient elevation to accommodate the gage bar on the platen-displacing frame and the carbon-carrier handle, and a transparent wall at the front to permit work on the platen to be 80 viewed, said transparent wall being shiftable with reference to the rest of the cover to permit access to the machine at the front of the carriage.
10. A sound-deadening casing for a machine of the class described, having at its front an opening through which the keyboard projects and a slot through which controlling handles project from the carriage, and comprising a body-portion and a cover hinged at its top and rear to said body-portion and having a ceiling at a sufficient elevation to accommodate the gage bar on the platen-displacing frame and the carbon-carrier handle, and a transparent wall at the front to permit work on the platen to be 85 viewed, said transparent wall being shiftable with reference to the rest of the cover to permit access to the machine at the front of the carriage.
11. A sound-deadening casing for a machine of the class described, having at its front an opening through which the keyboard projects and a slot through which controlling handles project from the carriage, and comprising a body-portion and a cover hinged at its top and rear to said body-portion and having a ceiling at a sufficient elevation to accommodate the gage bar on the platen-displacing frame and the carbon-carrier handle, and a transparent wall at the front to permit work on the platen to be 90 viewed, said transparent wall being shiftable with reference to the rest of the cover to permit access to the machine at the front of the carriage.
12. A sound-deadening casing for a machine of the class described, having at its front an opening through which the keyboard projects and a slot through which controlling handles project from the carriage, and comprising a body-portion and a cover hinged at its top and rear to said body-portion and having a ceiling at a sufficient elevation to accommodate the gage bar on the platen-displacing frame and the carbon-carrier handle, and a transparent wall at the front to permit work on the platen to be 95 viewed, said transparent wall being shiftable with reference to the rest of the cover to permit access to the machine at the front of the carriage.
13. A sound-deadening casing for a machine of the class described, having at its front an opening through which the keyboard projects and a slot through which controlling handles project from the carriage, and comprising a body-portion and a cover hinged at its top and rear to said body-portion and having a ceiling at a sufficient elevation to accommodate the gage bar on the platen-displacing frame and the carbon-carrier handle, and a transparent wall at the front to permit work on the platen to be 100 viewed, said transparent wall being shiftable with reference to the rest of the cover to permit access to the machine at the front of the carriage.
14. A sound-deadening casing for a machine of the class described, having at its front an opening through which the keyboard projects and a slot through which controlling handles project from the carriage, and comprising a body-portion and a cover hinged at its top and rear to said body-portion and having a ceiling at a sufficient elevation to accommodate the gage bar on the platen-displacing frame and the carbon-carrier handle, and a transparent wall at the front to permit work on the platen to be 105 viewed, said transparent wall being shiftable with reference to the rest of the cover to permit access to the machine at the front of the carriage.
15. A sound-deadening casing for a machine of the class described, having at its front an opening through which the keyboard projects and a slot through which controlling handles project from the carriage, and comprising a body-portion and a cover hinged at its top and rear to said body-portion and having a ceiling at a sufficient elevation to accommodate the gage bar on the platen-displacing frame and the carbon-carrier handle, and a transparent wall at the front to permit work on the platen to be 110 viewed, said transparent wall being shiftable with reference to the rest of the cover to permit access to the machine at the front of the carriage.
16. A sound-deadening casing for a machine of the class described, having at its front an opening through which the keyboard projects and a slot through which controlling handles project from the carriage, and comprising a body-portion and a cover hinged at its top and rear to said body-portion and having a ceiling at a sufficient elevation to accommodate the gage bar on the platen-displacing frame and the carbon-carrier handle, and a transparent wall at the front to permit work on the platen to be 115 viewed, said transparent wall being shiftable with reference to the rest of the cover to permit access to the machine at the front of the carriage.
17. A sound-deadening casing for a machine of the class described, having at its front an opening through which the keyboard projects and a slot through which controlling handles project from the carriage, and comprising a body-portion and a cover hinged at its top and rear to said body-portion and having a ceiling at a sufficient elevation to accommodate the gage bar on the platen-displacing frame and the carbon-carrier handle, and a transparent wall at the front to permit work on the platen to be 120 viewed, said transparent wall being shiftable with reference to the rest of the cover to permit access to the machine at the front of the carriage.
18. A sound-deadening casing for a machine of the class described, having at its front an opening through which the keyboard projects and a slot through which controlling handles project from the carriage, and comprising a body-portion and a cover hinged at its top and rear to said body-portion and having a ceiling at a sufficient elevation to accommodate the gage bar on the platen-displacing frame and the carbon-carrier handle, and a transparent wall at the front to permit work on the platen to be 125 viewed, said transparent wall being shiftable with reference to the rest of the cover to permit access to the machine at the front of the carriage.
19. A sound-deadening casing for a machine of the class described, having at its front an opening through which the keyboard projects and a slot through which controlling handles project from the carriage, and comprising a body-portion and a cover hinged at its top and rear to said body-portion and having a ceiling at a sufficient elevation to accommodate the gage bar on the platen-displacing frame and the carbon-carrier handle, and a transparent wall at the front to permit work on the platen to be 130 viewed, said transparent wall being shiftable with reference to the rest of the cover to permit access to the machine at the front of the carriage.

permit access to the machine at the front of the carriage, and supported by the rest of the cover so as to be shiftable therewith.

5 12. A sound-deadening casing for a machine of the class described, comprising a main portion to surround the machine, overhangs at the sides of the main portion to accommodate the travel of the typewriter carriage and the carbon-carrier-extension thereof, and a rearward overhang to accommodate the rear end of said extension, said rearward overhang having a slot in its bottom to permit the passage of webs from the 10 outside of the casing to the rear end of said extension.

13. A casing to enclose and deaden the sound of operation of a continuous billing typewriting machine having a carriage and a rearward extension of said carriage over which extension are fed plies of work-webs upwardly from a supply at the rear, said casing comprising a body-part and a cover-part, said body-part having lateral overhangs in which said carriage operates, and a rearward extension in which said carriage-extension operates, said rearward extension of the body-part comprising a rearward overhang and a slot in the bottom of said 25 rearward overhang beneath the rearward end of said carriage-extension to provide for the passage of the work-webs upwardly to the rear of the carriage-extension and for lateral movements of the webs with said 30 carriage, and flexible means for holding the work-webs at a tension as they pass through the slot.

14. A sound-deadening casing for a typewriting machine of the fan-fold type, said 40 casing comprising a main cover which, when raised, exposes said machine from front to rear to permit displacement of the platen to release the web-plies in use and rearward movement of the carbon-carrier, by its handle, to shift carbon-sheets, interleaved between said web-plies, to fresh sections of the web-plies, and an auxiliary cover at the front which, when there is no requirement for raising the main cover, may be shifted 45 to expose the platen and a smaller portion of the adjacent parts, said auxiliary cover hinged to the forward end of the main cover.

15. A sound-deadening casing for a continuous billing typewriting machine comprising a platen around which may be fed continuous web-plies and interleaved carbon-sheets, a carriage for said platen, feed-rolls mounted in said carriage to co-operate with the platen to feed said web-plies, a 50 gage device extending upwardly from the delivery side of the platen and swingable forwardly to straighten said webs and separate the platen and feed-rolls, and an operating handle extending forwardly from the 55 carriage and traveling therewith, said cas-

ing comprising a body-part having rearwardly-located means for passing the web-plies to the carriage, and a front wall, along the top of which said handle travels, and laterally-projecting overhangs to accommodate the travel of the carriage and its extension, and a cover forming with the front wall of the body-part a slot through which said handle projects and so connected with the body-part as to permit its forward end to be raised sufficiently to permit the forward swing of said gage device and the gaging of the web-plies thereby. 70

16. A sound-deadening casing for a continuous billing typewriting machine comprising a platen around which may be fed continuous web-plies and interleaved carbon-sheets, a carriage for said platen, feed-rolls mounted in said carriage to co-operate with the platen to feed said web-plies, a gage device extending upwardly from the delivery side of the platen and swingable forwardly to straighten said webs and separate the platen and feed-rolls, and an operating handle extending forwardly from the carriage and traveling therewith, said casing comprising a body-part having at the rear a slot through which the continuous web-plies pass to the carriage and along which the web-plies travel with the carriage; and comprising a front wall, along the top of which said handle travels, and laterally-projecting overhangs to accommodate the travel of the carriage and its extension, and a cover forming with the front wall of the body-part a slot through which said handle projects and so connected with the body-part as to permit its forward end to be raised sufficiently to permit the forward swing of said gage device and the gaging of the web-plies thereby. 80

17. A sound-deadening casing for a machine of the class described, comprising a body-portion to receive the machine and having a front wall, the upper edge of which contacts with an operating handle projecting forwardly from the carriage, laterally-extending overhangs to accommodate the travel of the carriage and the carbon-carrier extension, a rearward overhang to accommodate the rear end of said extension and having a slot in its bottom to permit the passage of continuous webs to the rear end of said extension, and a roof over said rearward overhang; and a cover pivoted to the forward edge of said roof and co-operating at its forward edge with the upper edge of the front wall of the body-portion to form a slot along which said operating handle travels. 90

18. A sound-deadening casing for a machine of the class described, comprising a body-portion to receive the machine and having a front wall, the upper edge of which contacts with an operating handle projecting forwardly from the carriage, laterally-extending overhangs to accommodate the travel 100

of the carriage and the carbon-carrier extension, a rearward overhang to accommodate the rear end of said extension and having a slot in its bottom to permit the passage of continuous webs to the rear end of said extension, and a roof over said rearward overhang; a cover pivoted to the forward edge of said roof and co-operating at its forward edge with the upper edge of the front wall of the body-portion to form a slot along which said operating handle travels; and means to hold said pivoted cover in such raised position as to provide clearance for the gage-frame when swung forwardly to release the webs preparatory to gaging their forward ends.

19. A sound-deadening casing for a machine of the class described, comprising a body-portion to receive the machine and

having a front wall, the upper edge of which contacts with a line-space handle projecting forwardly from the carriage at one end and with a carriage-release handle at the other end of the carriage, laterally-extending overhangs to accommodate the travel of the carriage and the carbon-carrier extension, a rearward overhang to accommodate the rear end of said extension and having a slot in its bottom to permit the passage of continuous webs to the rear end of said extension, and a roof over said rearward overhang; and a cover pivoted to the forward edge of said roof and co-operating at its forward edge with the upper edge of the front wall of the body-portion to form a slot along which said handles travel.

JOHN WALDHEIM.
